UNITED STATES PATENT OFFICE

150,415

DESIGN FOR A RAILWAY VEHICLE

Ralph W. Haman, Flossmoor, and Stanley W. Kay, Chicago, Ill., assignors to Pullman-Standard Car Manufacturing Company, Chicago, Ill., a corporation of Delaware

Application June 28, 1946, Serial No. 131,124

Term of patent 14 years

(Cl. D66—1)

To all whom it may concern:

Be it known that we, Ralph W. Haman and Stanley W. Kay, citizens of the United States, and residents, respectively, of Flossmoor, county of Cook, and State of Illinois, and Chicago, county of Cook, and State of Illinois, have invented a new, original, and ornamental Design for Railway Vehicle, of which the following is a specification, reference being had to the accompanying drawings, forming part thereof.

In the drawings—

Fig. 1 is a general plan view of a portion of a railway vehicle of our new design showing the grill room and food bar in this portion of the vehicle;

Fig. 2 also is a general plan view, but illustrating the opposite portion of the vehicle complementary to that indicated in Fig. 1 and showing the grill room and food bar in this portion of the vehicle;

Fig. 3 is a general perspective view of the grill room illustrated in Fig. 1, looking toward the food bar, and having portions broken away to afford a better illustration of the interior;

Fig. 4 is a general perspective view of the grill room illustrated in Fig. 2, looking away from the food bar, and having portions broken away better to reveal the interior design.

Fig. 5 is a general perspective view of a conventional railway car body of the type in which our new design is incorporated, and indicating the supporting trucks in dotted lines;

Fig. 6 is a perspective view to larger scale of a food serving bar at the pantry end of one of the grill rooms; and

Fig. 7 also is a perspective to larger scale showing the opposite end of a grill room from the food bar.

The characteristic features of the present design are shown by means of full lines in the drawings and reside in the grillrooms in the interior portions of the vehicle.

We claim:

The ornamental design for a railway vehicle, substantially as shown and described.

RALPH W. HAMAN.
STANLEY W. KAY.
